UNITED STATES PATENT OFFICE

JAMES WILLARD HARVEY, OF WINTHROP, MAINE

MOTOR BOAT INSTALLATION

Application filed December 15, 1930. Serial No. 502,411.

My invention relates to constructions of the general character set forth in my Patent #1,786,997, dated December 30, 1930.

One object of the present invention is to construct the parts so that they can be compactly arranged and more easily installed.

Another object is to mount the movable parts in such a way that the propeller can be more easily raised in case it strikes an obstacle when the boat is traveling forward.

Another object is to eliminate external projections and protect the swinging arms entirely within the casing.

Another object is to simplify the construction.

I have shown three modifications of my present invention, each having its own advantages with respect to different types of power units.

Fig. 1 is a longitudinal section and side view of one form of construction in which the power unit is complete in itself and has the cooling water intake and exhaust passages for the motor and may be rotated on a vertical axis for the purpose of steering.

Fig. 2 is a horizontal section and plan, the section being taken on the plane of the line 2-2 of Fig. 1.

Fig. 3 is a side view and longitudinal section of another modification in which the motor and the water inlet and exhaust passages are carried by the removable bottom plate or closure, and the propeller shaft housing may be rotatable for the purpose of steering.

Fig. 4 is a longitudinal sectional view and partial side elevation of another modification in which the entire power unit is supported in the bottom plate which may be rotatable on a vertical axis for the purpose of steering.

My former patent shows one method of installing such a construction in a boat preferably at a point intermediate the beam and stern and forward of the stern. It will be understood, of course, that this is applicable to various designs of boats without regard to the shape of the stern.

Preferably the casing 7 has a bottom flange 8 and is secured in an opening in the bottom

9 of the boat. The casing itself may be formed of an integral casting having a portion 10 which is closed and an opening 11 at the rear end. A closure plate 12 is fitted to this opening 11 and adapted to be moved into and out of place in the opening. For convenience in manufacture the opening 11 and the plate 12 are circular, and in some forms of the device the plate may be rotatable.

In the form of Fig. 1 an upright post or pillar 13 has a bottom flange 14 secured to the bottom plate 12. This post 13 may conveniently be of channel-like form as shown in the section of Fig. 2 and is connected at its lower end to the casing by an arm 15 having two parts, each of which is hinged to a lug 16 integral with the bottom of the casing and hinged at 17 to one of the side flanges of the post 13 close to the bottom. This post 13 is also connected to the casing by a link or arm 18 having two parts, each of which is hinged to a lug at 19 integral with the bottom and/or side wall of the casing. The other end of each part of this arm 18 is hinged to the post at 20 near the top of the post.

The side arms 18 may be jointed as indicated at 18' to facilitate the raising and inspection of the propeller as will be herein-after understood.

The power unit may have a motor 21 of any suitable type whose purpose, of course, is to drive the propeller 22. The frame of the motor may have depending feet 23 supported on the top of the post 13 in any suitable manner.

The usual tubular housing 24 encloses the driving shaft and extends downward to the bottom plate 12. The part 25 of the propeller housing may serve as a rudder as is common in outboard motor practice. The tubular part of the housing is preferably supported in bearings formed at the upper and lower portions of the post 13 and held in place by detachable bearing caps 26 and 27.

The housing in this form of construction may be provided with an inlet 28 for the cooling water for the motor. The cooling water may be discharged through the water outlet 29 or with the exhaust from the motor through the outlet 30.

A drain outlet 31 is also preferably provided in some part of the bottom of the casing, as for instance in the plate 12 so that when the boat is in motion the water in the 5 casing will automatically be drawn out.

The motor or the propeller housing may be rotated by means of a drum 32 and cable connections such as shown in my application #483,780, or it may be turned by a handle 10 33 if desired.

The construction and arrangement of the swinging arms or links 15 and 18 is such that if the propeller guard 34 meets an obstruction it will immediately yield rearwardly and 15 upwardly, thus avoiding damage.

The weight of the motor and its frame and the bottom plate 12 is sufficient under ordinary circumstances to hold the propeller in place. I may, however, provide a handle 35 20 attached to the motor frame or the housing in any suitable manner, as for instance by a cable 36, to facilitate lifting the propeller out of the water either temporarily or when it is desired to lay up the boat.

25 In the ordinary lifting of the propeller the two arms 15 and 18 swing about their forward ends and the propeller is lifted up through the opening in the bottom of the casing until it clears the bottom of the boat at 30 which time the arm 18 will be substantially vertical and the housing 24 will be inclined at a considerable angle to the horizontal. Further pull on the handle 35 causes the friction or spring tight joints 18' to yield 35 and allow the upper forward end of the motor to swing still farther forward and downward, thus further raising the propeller to a point where it can be more easily reached and where the weight of the parts is better 40 disposed for stability.

In the construction shown in Fig. 3 the casing 40 has an opening in the bottom normally closed by the plate 41 which is not intended to be rotatable although it may be 45 circular as in the form shown in Fig. 2 for convenience in manufacture.

This construction also has a vertical post or pillar 42 secured to the bottom plate or closure 41 in any suitable manner. This post 50 is connected to the casing by links or arms 43 and 44 similar to those above described so that the post 42 and the bottom plate 41 may have a swinging movement up into the casing.

55 A motor 45 of any suitable type drives the propeller 46 through a shaft 47 and bevel gear connection as usual in motors of this type. The motor may be supported in any suitable manner on the upper end of the post 60 42, and the housing 48 is rotatably supported by the post 42 and held in place by bearing caps such as 49 at the top and bottom. This housing 48 has a collar 50 at its upper end by which it may be rotated with the aid of a 65 handle 51 for the purpose of steering, the mo-

tor itself being stationary with respect to the post 42 and bottom plate 41 which constitute the tilting frame.

In this case the water inlet 52 is in the bottom plate 41 and connected by a suitable pipe to the motor. A pump 53 of any suitable type may be employed to insure adequate cooling water circulation when the boat is stationary. This pump is mounted upon and of course movable with the tilting frame. The exhaust 1 pipe 54 discharges directly through the bottom plate 41. It will thus be seen that in a construction of this character the cooling water and exhaust passages are independent of the propeller shaft housing 48. In such a construction the propeller shaft housing might be made removable for purpose of assembly and repair.

The water inlet might be located close to the propeller as in Fig. 1 in which case the propeller serves to aid in the water circulation without any separate pump.

In the form shown in Fig. 4 the plate 60 normally closes an opening 61 which is formed in the bottom of the casing 62. This plate is rotatable and a yielding gasket 63 is preferably provided.

The motor 64 may be of any suitable type and has a depending housing 65 secured for instance by bolts 66 to the upper face of the 6 movable bottom plate 60. The housing 67 is suspended from the bottom of the plate 60 by rods such as 68. The housings carry the water inlet and exhaust outlet passages 69 and 70 respectively.

The housing also supports the vertical shaft 71 and the horizontal shaft 72 and gears for driving the propeller 73 in the usual manner. This may also embody reversing means 74 and an operating rod 75 controlled 1 in any well known manner.

This entire housing construction may be provided with means such as a drum 76 for rotating it on a vertical axis for the purpose of steering.

The sleeve or upright member 77 may be detachably connected to support the housing 65 and for this purpose bearing caps 78 may be provided detachably secured to the main body of the sleeve in the usual manner.

A top plate 79 may be secured to the upper end of the housing 65 and seat in a supporting plate 80 for additional stability if desired as in my former patent.

It will be understood, of course, that this form of construction also preferably employs swinging arms such as 81 and 82 for the purpose of tilting the power unit as heretofore described with reference to the other forms of the invention.

In this case the arms 81 and 82 are hinged to the sleeve 77 which corresponds in this respect to the post 13 shown in Fig. 1.

In the type of construction shown in Fig. 4 where the housing above the movable bottom

plate is of substantial cross section it will be understood that many conveniences and arrangements may be provided, for instance such a construction permits of the use of an impeller or a centrifugal pump, reduction gearing or reversing mechanism whereby the vertical propeller shaft may be reversed.

It will be seen from the foregoing that the invention herein claimed is capable of adaptation to various forms of motors. While certain features of the invention are particularly applicable to what are commonly termed outboard motors where the boat is steered by the rotation of the propeller housing on a vertical axis, it should be understood that many of the features are equally useful in installations which employ separate rudders for the purpose of steering. Although the power unit may itself carry the fuel reservoir it should be understood that a separate reservoir may be employed if desired, as set forth in my former application.

Location of the water inlet beneath the bottom of the boat provides a more efficient water cooling system as there is less air entrained with the water than is the case when the propeller and water inlet is at the stern in the wake of the boat. This inboard casing installation also permits of a shorter shaft housing and a lower motor so that the cooling water does not have to be lifted as high as in the usual outboard motor.

Mechanism embodying the foregoing features has been found to provide an extremely convenient method of installation, great stability and convenience of operation, and it also results in more efficient application of power.

Altho this invention is especially adapted to so called outboard motors which are mounted directly on the upper end of the housing, some of the advantages might be had from the use of a stationary type motor mounted alongside of the casing and connected to the propeller shaft by flexible power transmission mechanism permitting the tilting action of the propeller as herein set forth. In such case it is desirable to provide a water inlet in the stationary bottom of the casing and a motor exhaust through the bottom. The drain 31 may also be located in the fixed bottom plate.

I claim:

1. A motor installation comprising a casing having an opening in the bottom, a closure for said opening, a rotatable propeller shaft extending through said closure, a housing for said shaft, a bearing member for said housing, a pair of swinging arms each hinged at one end within said casing and hinged at the other end to said bearing member.

2. In a motor installation, a casing having an opening in the bottom, a closure for said opening, a propeller shaft extending through said closure, a housing for said shaft, a pro-

peller carried by said housing beneath said closure, a pair of swinging arms each hinged at one end within said casing and having a hinged connection at its other end to said housing.

3. A motor boat installation comprising a casing adapted to be secured to the bottom of a boat and having an opening in the bottom, a propeller supporting frame including a vertical housing for the propeller shaft, two arms one above the other hinged at their forward ends within said casing near the front end thereof, the lower arm having a hinged connection with the housing near the bottom of the boat, the other upper arm having a hinged connection with the housing above the hinged connection of the other arm, the said upper arm having its forward end hinged to the casing forward of the forward end of the lower arm.

4. A motor installation comprising a casing having a bottom opening, a housing carrying a propeller movable through said opening, two swinging arms having a hinged connection with said housing, one of said arms being jointed intermediate its ends to permit extra inclination of the housing.

5. A motor installation comprising a casing having a bottom opening, a housing carrying a propeller movable through said opening, two swinging arms having a hinged connection with said housing and said casing, one arm being above the other and the upper of said arms being jointed intermediate its ends to permit extra inclination of the housing.

6. A motor installation as set forth in claim 1 in which one arm is movable above the other and provided with a folding joint.

7. A motor installation as set forth in claim 3 having a folding joint in the upper arm.

8. A motor installation comprising a casing having an opening in the bottom, a movable plate for closing said opening, a post secured to said plate, a propeller shaft housing secured to said post, a motor for driving the propeller, a cooling water inlet through said bottom plate and an exhaust outlet through said plate.

9. A motor installation comprising a casing having an opening in the bottom, a movable plate for closing said opening, a post secured to said plate, a propeller shaft housing secured to said post, a motor for driving the propeller, a cooling water inlet through said bottom plate and an exhaust outlet through said plate, the propeller shaft housing being rotatable independently of the inlet and exhaust connection.

10. In a motor installation, a casing having a bottom opening, a plate closing said opening, a propeller housing rotatable in said plate, a post secured to said plate, hinged supports for the upper and lower ends of

said post to permit it to tilt with the propeller housing, and a motor exhaust pipe separate from said housing, and discharging through said plate.

5 11. A motor installation comprising, a casing having a bottom opening, a plate closing said opening, a propeller housing extending through said plate, hinged supporting members connected to the upper and 10 lower ends of said housing to permit it to tilt, a water inlet and a motor exhaust pipe separate from said housing discharging through said plate.

12. A motor installation comprising a casing having a bottom opening, a plate rotatable in said opening, a housing secured to and rotatable with the plate, a tilting sleeve affording a bearing and support for 15 said housing, said housing having a propeller and a water inlet and an exhaust outlet.

20 13. A motor installation comprising a casing having a bottom opening, a plate rotatable in said opening, a housing secured to and rotatable with the plate, a tilting sleeve 25 affording a support for said housing, said housing having a propeller on its lower end and two arms hinged to said casing and said sleeve.

30 14. In a motor installation a casing having a bottom opening, a plate for closing said opening, a propeller housing having a lower portion secured beneath said plate and having a water inlet, a propeller and reversing means, and an upper housing portion secured above said plate and supporting means 35 for the upper part of the housing.

40 15. A motor boat installation comprising a casing secured to the bottom of the boat forward of the stern and having a bottom plate with an opening therein, a removable bottom plate for closing said opening, a motor having a water inlet and an exhaust through one of said bottom plates, a propeller shaft housing secured to and having a 45 portion projecting downwardly from the removable bottom plate, a propeller carried by said housing beneath the bottom plate, a swinging arm hinged in the casing and having a hinged connection with said housing 50 adjacent the removable bottom plate, a second arm providing a swinging support for an upper part of said housing and power transmission mechanism connecting the motor with the propeller.

55 16. A motor boat installation comprising a casing secured in an opening in the bottom of the boat and having an opening in one portion of its bottom with a removable plate portion for closing the opening, a motor mounted adjacent the casing and having a water inlet through a portion of the bottom of the casing and having an exhaust discharging beneath the bottom of the casing, a propeller supported by and movable 60 with said removable plate portion up into

the casing, means for draining the casing when in motion and a power transmission connection between the motor and the propeller permitting the propeller to be moved up and down in the casing.

70 17. A motor boat installation comprising a casing open at the top and having an opening in one end of the bottom, a supporting frame having a plate for closing said opening, a motor unit carried by said frame having a power cylinder at the upper end over the opening at the top of the casing, and a propeller at its lower end beneath said plate and a tilting support for said frame entirely within the casing and connected at 75 one end to said frame and hinged at its other end to the inside of the casing near the bottom.
